UNITED STATES PATENT OFFICE.

ANGEL DE VELASCO, OF NEW YORK, N. Y.

DESIGN FOR AN AUTOMOBILE-BODY.

57,117.

Specification for Design.

Patented Feb. 22, 1921.

Application filed July 14, 1920. Serial No. 396,319. Term of patent 7 years.

To all whom it may concern:

Be it known that I, ANGEL DE VELASCO, a citizen of Cuba, and a resident of the city of New York, borough of Manhattan and the county and State of New York, have invented a new and Improved Design for an Automobile-Body, of which the following is a specification, reference being had to the accompanying drawing, forming part thereof, in which—

Figure 1 is a side elevation of the new design for an automobile body.

Fig. 2 is a plan view thereof.

I claim:

The ornamental design for an automobile body, substantially as shown.

ANGEL DE VELASCO.
